UNITED STATES PATENT OFFICE.

HARRY G. AINSWORTH, OF KENTLAND, INDIANA.

MECHANICAL MOVEMENT.

Application filed April 18, 1921. Serial No. 462,835.

To all whom it may concern:

Be it known that I, HARRY G. AINSWORTH, a citizen of the United States, residing at Kentland, in the county of New-ton and State of Indiana, have invented 5 certain new and useful Improvements in Mechanical Movements, of which the following is a specification, reference being had to the accompanying drawings, and to the 10 reference characters marked thereon, which form a part of this specification.

This invention relates to improvements in mechanical movements adapted for actuating garage doors.

15 The object of the invention is to provide an actuating mechanism that may be set into operation by turning or throwing a switch in an electric circuit and thereby move the door, whether it be a door that 20 is raised and lowered, or one that has a sliding movement.

Another object of the invention is to produce a relatively cheap operative device, which is mounted as a unit on a frame and 25 which may therefore be readily installed without the aid of skilled labor, and one which is not liable to get out of order.

For the accomplishment of these and other objects which will become manifest 30 as I proceed with my specification, the invention consists in the devices and combination of devices herein illustrated, described and claimed.

While the mechanism is applicable to various uses, I have chosen to illustrate it as 35 adapted to the operation of the doors of a garage.

In that form of the invention shown in the drawings, Fig. 1 is a side elevation of 40 the device embodying my invention, the door being shown in section.

Fig. 2 is a side view of a detail, shown in a different position from its position in Fig. 1.

45 Fig. 3 is a vertical sectional view of a detail taken upon the plane of the line 3—3 of Fig. 4.

Fig. 4 is a top plan view of the device.

Figs. 5 and 6 are side views showing modified applications of attachment to doors.

Figs. 7 and 8 are diagrammatic views of the electric circuit, showing the circuit open in Fig. 7 and closed in Fig. 8.

55 Fig. 9 is a detail showing operative gears in the electric circuit.

The mechanism is mounted upon a cast

metal frame A, which may be secured to a stationary support through the bolt holes 1, or in any other suitable manner.

Referring now more particularly to Figs. 60 1 and 2, the door to be raised and lowered by this mechanism is shown at D, and the motive power is indicated by the motor M, suitably mounted upon the platform 2 of 65 the frame A.

Mounted in suitable bearings 3 on the other end of the frame is a driven shaft 4, and upon this shaft are a pair of sleeve pulleys 5, indicated by dotted lines, which pulleys are protected by a housing 6 on the 70 frame A. Cables or chains 7 secured at one end to the pulley 5, are secured at their other end to the top of the door D. The raising or lowering of the door follows when the shaft 4 is rotated. Mounted upon 75 the end of the shaft 4 is a spur pinion 8, its teeth being in mesh with the teeth of a segmental gear 9.

Depending from the under side of the frame is a bracket 10 secured to the frame 80 by any suitable means, as by bolts 11, and braced by the bar 12. A stub shaft 13 is mounted at one end in the bracket 10. The segmental gear 9 is pivotally mounted at 14 upon the stub shaft 13 and swings about 85 said shaft as a fulcrum.

Journaled in bearings 15 upon the frame A is the main driving shaft S, and in suitable bearings 16 is a stub shaft 17, and in bearings 18 is a stub shaft 19. The set of 90 bearings 16 and 18 are in standard 20 upon the side members 21, 22, of the frame A. Upon the shaft 23 of the motor M is a small belt pulley 24 which is connected with a belt pulley 25 on the stub shaft 19 by a 95 belt 26. Motion is thus transmitted from the motor to the shaft 19 and the spur pinion 27 thereon. This pinion 27 meshes with the teeth of a spur gear 28 on the shaft 17 and drives said gear 28. A spur pinion 29 is 100 also mounted upon the shaft 17 and meshes with a large spur gear 30 mounted to rotate upon the shaft S.

Upon the end of the shaft S is a crank C, its free end being pivotally attached at 105 36 to one end of a connecting link L. The other end of the link L is pivotally attached at 37 to the segmental gear 9.

The motor M is in an electrical circuit containing an automatic three-way switch 110 41 and at least two other operating switches 42, 43, the switch 43 being shown as a

four-way switch. The switch 41 is mounted in circuit on the frame member 22, the switch shaft 44 being parallel with the shaft S. The shaft 44 is provided with a spur gear 45, which is in mesh with the spur pinion 46 on the shaft S. The gear 45 has twice the number of teeth that are provided for the pinion 46.

In Fig. 7, the switch 41 is shown on contact points 47, 47, and the switch 42 on contact points 48, 48. The switch 43 is shown open, by joining contact points 49, 50, and 51, 52.

In Fig. 8, the switch 43 has been shifted so that the line containing contact points 50, 52 is closed, and the line containing contact points 49, 51, is open. Thus the current will run from the line 53 to the motor M, from thence by line 54 through switch 41, to line 55, switch 43, line 56, switch 42 and line 57, back to the source of electrical energy. The circuit may be opened by throwing the switch 42 or the switch 43 or any other switch that may be in circuit.

From the foregoing it will be understood that the operation of the parts is as follows: the circuit and switches being as indicated in Fig. 7, and the mechanical parts being positioned as shown in Fig. 1,—that is to say, with the doors D raised to their uppermost position, the operation of say, the switch 43 from the position shown in Fig. 7 to the position shown in Fig. 8, will close the circuit. The current will of course instantaneously cause the rotation of the motor, which in turn through the belt connections will operate the shaft 19, and through the connecting gears, the shaft 17, and finally the main shaft 30. The rotation of the main shaft will cause the crank C to swing from the position shown in Fig. 1 to that shown in Fig. 2. The current through the link L will likewise rock the segmental gear 9 from the position shown in Fig. 1 to the position shown in Fig. 2, the segmental gear 9 in its turn actuating the pinion 8 and the pulley shaft 4, thus unwinding the cable 7 and permitting the door to descend.

It will be manifest that the travel of the door in going from the lower to the raised position or vice versa, must be accomplished simultaneously with one complete rocking movement in one direction of the segmental gear 9. In order, therefore to stop the movement of the parts when the segmental gear has reached the limit of its throw, the circuit must be automatically broken. This I accomplish by reason of the fact that the rotation of the shaft S one-half of a turn will rotate the shaft 44 of the automatic switch 41, a quarter of a turn only. The ratio of the gearing 45 and 46 being two to one. This turning of the switch shaft 44 will throw the switch 41 from the contact points 47, 47, into the position shown in

dotted lines in Fig. 8, into contact with the points 58, 58, thus breaking the circuit, with the result that the motor instantly stops. The contact point 58 is now connected with the line 59, contacts 51, 49, and line 60. To again operate the mechanism and raise the door into the position shown in Fig. 1, either the switch 43 may be turned so as to close the contacts 51, 52, or the switch 42 may be turned to close contacts 61, 62, as indicated by the dotted line in Fig. 8, whereupon by the rotation of the shaft S one-half of a turn, the gears 45, 46, will again actuate the switch shaft 44 and cause the switch 41 to leave contacts 48 and close contacts 47, thus again breaking the circuit. These various electrical features will be understood by those skilled in the art and need not be further elaborated.

Of course, it will be understood that where my mechanism is applied inside of a garage to operate the doors, one of the switches 42 or 43 as the case may be, will be located inside of the building and one outside of the building. The operation of either switch causes the mechanism to raise the doors if they are lowered, and to lower the doors if they happen to be raised.

In the modification shown in Fig. 5, the door is provided with a counter-balancing weight W and the cables 7 instead of being attached at one end to the sheaves or pulleys 5, are first trained over pulleys 38 secured in bracket bearings 39 to the ceiling 40, then wrapped about the sheave pulleys 5 and finally secured at their ends to the counter-balancing weight W.

In the modification shown in Fig. 6, the sheave pulleys 5 and the cables 7 are dispensed with and the door D is suspended by brackets 63 from a horizontally disposed carrying rail 64 to travel thereover. In such case, the top of the door D is provided with a rack bar 65, the teeth of which engage the under side of and mesh with the teeth of a gear 66 mounted on the shaft 4.

I claim as my invention:

1. A mechanical movement comprising a driven rock shaft, a spur pinion thereon, a segmental gear in mesh with the pinion, a rotatable drive shaft, a rotatable crank on the drive shaft, a link arm operatively connecting the crank and the segmental gear, and means for operating the drive shaft a half revolution at a time.

2. A mechanical movement comprising a driven rock shaft, a spur pinion thereon, a segmental gear in mesh with the pinion, a rotatable drive shaft, a rotatable crank on the drive shaft, a link arm operatively connecting the crank and the segmental gear, and means for operating the drive shaft a half revolution at a time, said means including a motor and operative connections between the motor and the drive shaft.

3. A mechanical movement comprising a driven rock shaft, a spur pinion thereon, a segmental gear in mesh with the pinion, a rotatable drive shaft, a rotatable crank on the drive shaft, a link arm operatively connecting the crank and the segmental gear, a rotatable gear mounted on the drive shaft, a motor for operating the drive shaft one half revolution at a time, complementary members between the motor and the drive shaft for operating the motor, and means for controlling the latter.

4. A mechanical movement comprising a driven rock shaft, a spur pinion thereon, a segmental gear in mesh with the pinion, a rotatable drive shaft, a rotatable crank on the drive shaft, a link arm operatively connecting the crank and the segmental gear, and means for operating the drive shaft a half revolution at a time, said means including an electric circuit and a motor in said circuit.

5. A mechanical movement comprising a driven rock shaft, a spur pinion thereon, a segmental gear in mesh with the pinion, a rotatable drive shaft, a rotatable crank on the drive shaft, a link arm operatively connecting the crank and the segmental gear, means for operating the drive shaft a half revolution at a time, and a driven element operatively associated with the driven shaft.

6. A mechanical movement comprising a driven rock shaft, a spur pinion thereon, a segmental gear in mesh with the pinion, a rotatable drive shaft, a crank on the drive shaft, a link arm operatively connecting the crank and the segmental gear, means for operating the drive shaft a half revolution at a time, a reciprocating element and means operatively connecting the reciprocating element with the rock shaft.

7. In a device of the character described, the combination of a cast metal frame having a pair of side members, shaft bearings thereon, a rotatable drive shaft in said bearings, an extension table at one end of and integral with the frame, a motor thereon, shaft bearings at the other end of the frame, a rocking driven shaft in said last mentioned bearings, an upright standard on each side member, shaft bearings in each standard, a shaft in said standard bearings in operative connection with the drive shaft, a bracket secured to and depending from the

frame, a bearing in the bracket, a rotatable shaft in said bearing, a gear segment on the shaft, a rotatable crank on the drive shaft operatively connected to the gear segment, a pinion on the rocking driven shaft and in operative connection with the crank, the bores of the several shaft bearings being parallel and extending transversely of the frame, and means for actuating the drive shaft one half revolution at a time.

8. In a mechanical movement of the class described, a cast metal frame having a pair of side members, bearings therein for a drive shaft, an extension table at one end of the frame adapted to support a motor, bearings at the other end of the frame for a driven shaft, an upright standard on each side member, shaft bearings in each standard, a bracket depending from the frame and having a journal bearing therein, the bores of the several shaft bearings being parallel and extending transversely of the frame.

9. A mechanical movement comprising a rotatable shaft, motor driven means for actuating said shaft a half revolution at a time, a driven rock shaft, the longitudinal axes of the shafts being parallel, a pinion on the rock shaft, a rocking segmental gear in mesh with the pinion, a rotatable crank arm on the driving shaft, a link pivotally connecting the crank arm and the segmental gear, and means for operatively connecting the rock shaft to its work.

10. A mechanical movement comprising a rotatable shaft, motor driven means for actuating said shaft a half revolution at a time, a driven rock shaft, the longitudinal axes of the shafts being parallel and in different horizontal planes, a pinion on the rock shaft, a rocking segmental gear in mesh with the pinion, a rotatable crank arm on the driving shaft, a link pivotally connecting the crank arm and the segmental gear, and means for operatively connecting the rock shaft to its work.

In testimony, that I claim the foregoing as my invention I affix my signature, in the presence of two witnesses, this 14th day of April, 1921.

HARRY G. AINSWORTH.
